BENJAMIN G. LAMME, OF PITTSBURG, PENNSYLVANIA, ASSIGNOR TO
WESTINGHOUSE ELECTRIC & MANUFACTURING COMPANY, A COR-
PORATION OF PENNSYLVANIA.

CONTROLLING DEVICE.

No. 834,582.

Specification of Letters Patent.

Patented Oct. 30, 1906.

Application filed January 8, 1905. Serial No. 239,521.

To all whom it may concern:

Be it known that I, BENJAMIN G. LAMME, a citizen of the United States, and a resident of Pittsburg, in the county of Allegheny and State of Pennsylvania, have invented a new and useful Improvement in Controlling Devices, of which the following is a specification.

My invention relates to controlling means for translating devices that are adapted to be operated by either alternating or direct current energy.

The object of my invention is to provide systems which supply either alternating or direct current energy to translating devices, with means for preventing the application of energy to either of two sets of controlling devices of an amount or character for which it is not adapted.

Motors and other electrical translating devices have been constructed which may be operated by means of either alternating or direct current energy, and it frequently occurs that for economy in energy losses, and for other practical reasons it is desirable to employ controlling devices differing in character and construction according to the character of energy which is to be supplied through them. For instance, the voltage-regulating devices for use with alternating current may comprise transformers the voltage ratios of which are variable, regulators having primary and secondary windings the inductive relations of which are adjustable, or both, to which devices it would be dangerous to supply direct current.

My invention provides means for preventing the supply of direct current to the alternating-current controlling devices and for preventing the supply of alternating current to the direct-current controlling devices. It is also capable of broader application in that it may be employed for the purpose of insuring the supply of operative amounts of only one character of energy to given devices in a in a double-current system.

My invention is illustrated in the accompanying drawing, the single figure of which illustrates a system embodying my invention.

An alternating-current generator 1 delivers electrical energy to conductors 2 and 3,

and a direct-current generator 4 delivers energy to conductors 5 and 6. Any suitable current-collecting devices, such as trolleys 7 and 8, are adapted to make contact with the supply-conductors 2 and 3 and 5 and 6, these devices being connected, respectively, to terminals 9 and 10 of a double-throw switch 11. Terminals 12 and 13 of the switch 11 are respectively connected to contact-terminals 14 and 15 of circuit-breakers 16 and 17, the other terminals 18 and 19 of the circuit-breakers 16 and 17 being connected, respectively, to the middle points 20 and 21 of inductive windings 22 and 23.

A non-inductive resistance 24 is connected between one terminal of the inductive winding 22 and one terminal of the tripping-coil 25 of the circuit-breaker 16, the other terminals of the inductive winding 22 and the coil 25 being connected together and to one terminal of a non-inductive resistance device 26. The non-inductive resistance 26 is suitably subdivided by means of leads 27, that are respectively provided with contact-terminals 28, with which a pivoted arm 29 is adapted to engage, the arm 29 being connected to terminal 30 of switch 11 and to a terminal of the armature 31 of a motor 32.

One terminal of inductive resistance 23 and one terminal of tripping-coil 33 of circuit-breaker 17 are connected together. One terminal of a non-inductive resistance 34 is connected to the other terminal of the inductive resistance 23, and the remaining terminals of the coil 33 and the non-inductive resistance 34 are connected together and to one terminal of a transformer-winding 35, the other terminal of which is connected to one terminal of the armature 31 of the motor 32.

Connected to a suitable point 36 intermediate the end terminals of the transformer-winding 35 is one terminal of the secondary winding 37 of a series transformer 38, the other terminal of which is connected to a terminal 39 of a double-throw switch 40 with terminal 41 of switch 11 and with the middle point of an inductive winding 42. The primary winding 43 of the series transformer 38 is connected between terminals 44 and 45 of the double-throw switch 40, the terminal 46 of which is connected to a pivoted arm 47,

which is adapted to move over contact pieces 48, that are respectively connected by means of leads 49, to suitable points in the transformer-winding 35.

5 The devices just described comprise the means for varying the alternating-current voltage applied to the motor 32; but any other suitable means may be employed—such, for example, as a voltage-regulator substituted 10 in place of the series transformer 38, the voltage-regulator comprising primary and secondary windings the inductive relations of which are adjustable.

A non-inductive resistance 50 is connected 15 between one terminal of the inductive winding 42 and that terminal of field-magnet winding 51 which is connected to a terminal of the armature 31, the remaining terminals of the inductive winding 42 and the field-magnet winding 51 being connected together.

The operation of my invention may be understood from a consideration of that portion of the drawing which illustrates the direct-current-controlling devices. If trolley 7 25 and 8 engage conductors 5 and 6, respectively, and switch 11 is in the position shown, direct-current energy will be supplied to the motor 32 through supply-conductor 6, trolley 8, terminals 10 and 12 of switch 11, and

30 circuit-breaker 16, to the middle point of inductive winding 22, where the current divides, the larger portion traversing section 52 of the inductive resistance 22, to the non-inductive resistance 26, and the smaller portion traversing section 53 of the inductive resistance 22, non-inductive resistance 24 and coil 25, to the resistance 26, the circuit then continuing through resistance 26, arm 29, motor 32, resistances 42 and 50, terminals 41 and 9 35 of switch 11 and trolley 7, to the source 4. The larger portion of the current traverses the section 52 of the inductive resistance 22, because of the greater ohmic resistance of the circuit through the portion 53, inductive resistance 24, and coil 25.

The "inductive" resistances 22 and 23 are so termed because they possess very low ohmic resistance, but have comparatively high inductive resistance when energized with alternating current. The device 24 is so constructed as to have comparatively high ohmic resistance.

When the motor 32 is to be operated by alternating currents, the movable member of 55 the switch 11 is thrown to engage the terminals 13 and 30; but if the trolleys 7 and 8 should engage the conductors 2 and 3, respectively, while the switch 11 is in the position shown alternating-current energy 60 would be supplied through the circuit-breaker 16 to the middle point of the inductive winding 22. Since the two sections 52 and 53 are wound upon the same core in inductive relation to each other, approximately 65 equal currents traverse these sections and

sufficient energy is then supplied to the coil 70 to effect movement of its core 54, and thereby cause the circuit-breaker 16 to be opened.

In case it so happens that the trolleys 7 and 8 engage the conductors 5 and 6 when the movable member of the switch 11 is in engagement with the terminals 13 and 30 the circuit connections of the inductive and non-inductive resistances 23 and 34 and the coil 35 75 are such that the circuit-breaker 17 will be tripped, and since these connections may be readily understood from an inspection of the drawing and an understanding of the foregoing description it is deemed unnecessary to 80 describe them in detail.

I have also shown my invention as applied to the motor 32 for the purpose of automatically causing the ampere-turns in the field-magnet winding when it is energized by direct current to be greater than when it is energized by alternating current, such conditions being known to be desirable in practice. This latter arrangement is claimed in another application, Serial No. 206,186, filed by me May 3, 90 1904.

I claim as my invention—

1. The combination with a source of alternating-current energy, a source of direct-current energy, and a translating device adapted to be operated by either kind of energy, of a controlling device for each kind of energy and means for automatically opening the translating-device circuit when the energy supplied thereto is of the kind to which it is not adapted.

2. The combination with a source of alternating-current energy, a source of direct-current energy, and a translating device adapted to be operated from either source, of a controlling device for each kind of energy, circuit-breakers for the controlling-device circuits and means for tripping each circuit-breaker when the energy supplied to its circuit is of the kind to which it is not adapted.

3. The combination with a source of alternating-current energy, a source of direct-current energy, a translating device and means for connecting the same to either source, of a controlling device for each kind of energy, 115 circuit-breakers for the controlling-device circuits, and tripping devices therefor that operate only when the kind of energy supplied to the translating device is not adapted to the controlling device in service.

4. The combination with a source of alternating-current energy, a source of direct-current energy, and a translating device adapted to make circuit connections with either source, of means for interrupting said circuit 125 connections when the character of energy supplied therethrough is not suitable for the translating device.

5. The combination with a source of direct-current energy, a source of alternating-cur-

- rent energy, and a motor adapted for operation by either kind of energy, of a direct-current-controlling means, an alternating-current-controlling means, and an automatic protective device for each of said controlling means that interrupts the motor-circuit when the energy traversing the same is not the kind for which the controlling means is adapted.
10. 6. The combination with a source of direct-current energy, a source of alternating-current energy, and a motor adapted for operation by either kind of energy, of a direct-cur-
- rent controller, an alternating-current controller, a circuit-breaker for each controller, 15 and means for actuating each circuit-breaker when the energy supplied to its controller is not the kind for which it is adapted.
- In testimony whereof I have hereunto subscribed my name this 30th day of December, 20 1904.

BENJ. G. LAMME.
